Fig. 1

Fig. 3

Fig. 4

FIG. 1 is a side elevational view of a handle for a floral basket or similar article showing my new design; FIG. 2 is a top plan view thereof;

FIG. 3 is an end elevational view thereof; and

FIG. 4 is a fragmentary elevational view thereof on an enlarged scale of the lower right portion of FIG. 1.

The other side and end are substantially like the respective side and end shown in FIGS. 1 and 3. The bottom of the handle is substantially like the top thereof shown in FIG. 2. The V-pattern of one side is displaced by 180° from the V-pattern on the other side of the handle.

I claim:

The ornamental design for a handle for a floral basket or similar article, substantially as shown and described.
